RADIOTRANSMISSION OF FACSIMILES

Filed March 5, 1930

Fig. 2.

Inventor:
John W. Labus,
by *Charles O'Malley*
His Attorney.

UNITED STATES PATENT OFFICE

JOHN W. LABUS, OF SCHENECTADY, NEW YORK, ASSIGNOR TO GENERAL ELECTRIC COMPANY, A CORPORATION OF NEW YORK

RADIOTRANSMISSION OF FACSIMILES

Application filed March 5, 1930. Serial No. 433,457.

My invention relates to the transmission of facsimiles by radio. It has been found in the transmission of facsimiles by radio, particularly over long distances, that at certain times the received signal shows a lag in time thus producing in the case of the transmission of print a broadening of the letters. When conditions have been especially unfavorable and when small print is being transmitted the letters have become blurred and illegible. The cause of this phenomena apparently is due to multipath transmission of the radio signal arising from reflections from the Heaviside layer. It has been observed that the first edge of the letters with respect to the direction of scanning is clean cut whereas the blurring occurs at the opposite edge. It is the object of my invention to provide an improved method and means whereby such blurring of the received signal may be greatly reduced if not entirely eliminated.

My invention will be better understood from the following description taken in connection with the accompanying drawing, and its scope will be pointed out in the appended claims.

Referring to the drawing, Fig. 1 is a circuit diagram of receiving apparatus involving my invention; Fig. 2 shows by way of example a letter being transmitted; Figs. 3 and 4 are diagrams representing respectively blurred black and white signals received without my invention during the scanning of the letter shown in Fig. 2; and Fig. 5 is a similar diagram representing the black signals received with the use of my invention.

In the drawing forming a part of this application I have purposely omitted any showing of the sending apparatus since this may take the form of well known apparatus employed for this purpose with the exception that it includes a duplication of certain parts to the extent that both black signals and white signals are transmitted, the two signals being transmitted on two different channels. For this purpose two carriers may be used or one carrier wave may be beat by two tones, thus shifting the side bands such that they can be received without interference.

At the receiver two units will be used which

receive respectively the black and the white signals, the amplification and detection of the radio signals taking place in the ordinary way. These two units if used in the usual manner, independently of each other, would record the black and white signals in the manner shown by Figs. 3 and 4 respectively during the scanning at the sending station along the line $a-b$ of a letter such as shown for example at 1 in Fig. 2. The rectified black signal, shown plotted against time in Fig. 3, is sharp as at 2 at the first edge of the letter but at each last edge trails off in the irregular line 3-4 which, as already mentioned above, is due to the radio circuit. On the other hand the rectified white signal, shown plotted against time in Fig. 4, trails off in the irregular line 5 at the first edge of the letter and is sharp as shown at 6 at the last edge thereof. It will be understood that a facsimile may be transmitted by sending either black signals or white signals and from the diagrams forming Figs. 3 and 4 it will be seen that whichever signals are used for the transmission a blurring of the letter will occur at one side or the other thereof.

Referring now to Fig. 1, where I have shown in a diagrammatic manner portions of the two receiving sets 7 and 8 constructed and arranged respectively to receive the black and the white signals, each set 7 and 8 includes a three electrode thermionic amplifier 9 having a grid 10 and a plate 11, and a translating device 12 such as a glow tube by means of which the signal is recorded. A common plate battery 14 is shown for the two receiver sets 7 and 8. In the grid and plate circuits of the set 7 are the resistances 16 and 17 respectively and similarly in the grid and plate circuits of the set 8 are the resistances 18 and 19 respectively. By means of the conductors 20 the terminals of the resistance 19 are connected with the terminals of the resistance 16, the connection including the condenser 22 and in like manner by means of the conductors 23 the terminals of the resistance 17 are connected with the terminals of the resistance 18, the connection including the condenser 24.

With no signal being transmitted the grids

of the two receivers are biased to cut off. At the instant that the black signal current (Fig. 3) should stop, that is at the point 3, the white signal is received by the set 8 and an adequate voltage taken across the resistance 19 of the plate circuit of set 8 is applied to the grid circuit of set 7 to cause a cutting off of the output thereof. This voltage in magnitude is about equal to that of the grid voltage.

Without the condenser 22 the grid of set 7 would remain biased as long as the white signal was being received by set 8. For continuous operation therefore it is necessary that the inserted bias be taken off again in order that the receiver may be ready for the reception of the next signal. This result is effected by the condenser 22. At the instant the voltage is applied to it, it offers substantially no resistance but builds up a counter E. M. F. thereby restoring the original condition in the set 7. The result of applying this bias to the grid of black signal receiving set 7 is shown by Fig. 5 where the end of each black signal is seen at 25 to be cut off sharply. It may happen that after the signal has been cut off and the bias afterward removed the continued reception of the echo effect will cause a small hump as shown for example at 26. This, however, is not serious as the entire lower portion of the signal, together with the hump, may be cut off and discarded. In a manner similar to that just described, the white signal is caused to be cut off at the proper time by voltage applied to the grid of receiver 8 from the plate circuit of receiver 7, the entire system being symmetrical. Both translating devices 12 may be used to make records, the record made by one being a positive and the record made by the other being a negative. If but one record is to be made the device 12 which is not used may have substituted for it a suitable resistance.

I have chosen the particular embodiment described above as illustrative of my invention and it will be apparent that various modifications may be made without departing from the spirit and scope of my invention, which modifications I aim to cover by the appended claims.

What I claim as new and desire to secure by Letters Patent of the United States, is:—

1. In the transmission of facsimiles by radio wherein either black signals or white signals are transmitted to a receiving apparatus, the method which comprises transmitting concurrently on a different wave length the opposite signals to those being transmitted, and causing the latter signals to modify the operation of the receiving apparatus to produce a sharper recorded signal.

2. In the transmission of facsimiles by radio wherein either black signals or white signals are transmitted to a receiving appa-

ratus, the method of reducing the echo effect upon the receipt of the transmitted signals which comprises transmitting concurrently on a different wave length the opposite signals to those transmitted and causing the latter signals to effect a more sharp cutting off in the operation of the receiving apparatus.

3. Radio facsimile transmission apparatus comprising means for receiving black signals, means for receiving white signals, a translating device associated with one of said means for recording the signals thereof, and means responsive to the signal received by the other of said receiving means for reducing the echo effect on said first receiving means.

4. Radio facsimile transmission apparatus comprising separate means for receiving respectively black signals and white signals, a translating device connected to respond to the signals received by one of said receiving means, and means for applying to said one means a corrective impulse from the other receiving means.

5. Radio facsimile transmission apparatus comprising means adapted to receive either black signals or white signals, said means including a thermionic amplifier having a grid circuit and a plate circuit, a translating device connected with said plate circuit and means arranged to receive the signal opposite to that received by said first means for applying a biasing potential to said grid circuit.

6. Radio facsimile transmission apparatus comprising a first receiving means constructed to respond to black signals and including a thermionic amplifier having grid and plate circuits and a translating device connected with said plate circuit and a second receiving means constructed to respond to white signals arranged to apply a bias to said grid circuit at the beginning of each white signal.

7. Radio facsimile transmission apparatus comprising a first receiving means constructed to respond to black signals and including a thermionic amplifier having grid and plate circuits and a translating device connected with said plate circuit, a second receiving means constructed to respond to white signals arranged to apply a bias to said grid circuit at the beginning of each white signal, and means for removing said bias to prepare the black signal receiving means for the reception of the next signal.

8. Radio facsimile transmission apparatus comprising a receiver constructed to respond to black signals, said receiver including a thermionic amplifier having grid and plate circuits and a translating device connected with the plate circuit, a second similar receiver constructed to respond to white signals, and means whereby a biasing potential is applied to the grid circuit of each receiver from the plate circuit of the other receiver.

9. Radio facsimile transmission apparatus

comprising a receiver constructed to respond to black signals, said receiver including a thermionic amplifier having grid and plate circuits and a translating device connected with a plate circuit, a second similar receiver 5 constructed to respond to white signals, means whereby a biasing potential is applied to the grid circuit of each receiver from the plate circuit of the other receiver, and means for removing the biasing potential from each 10 grid circuit to prepare the receiver thereof for the next signal.

In witness whereof I have hereto set my hand this 4th day of March, 1930.

JOHN W. LABUS.
